UNITED STATES PATENT OFFICE.

MILES McINTYRE, OF HEALDSBURG, CALIFORNIA.

AUTOMOBILE TOOL.

Application filed April 13, 1922. Serial No. 552,195.

To all whom it may concern:

Be it known that I, MILES McINTYRE, a citizen of the United States, and a resident of Healdsburg, county of Sonoma and 5 State of California, have invented a new and useful Automobile Tool, of which the following is a specification.

The present invention relates to improvements in automobile tools and has particular reference to a tool for replacing transmission covers on Ford cars. The general structure of the Ford transmission is well known and comprises in its principal features three bands mounted on drums and 10 adapted to prevent rotary motion of their respective drums when compressed by means of foot pedals, the three bands representing forward motion, reverse, and brake. The shafts connected with the pedals and actuating the drums are mounted in the transmission cover, and when the latter has been removed for repairing purposes the bands rest loosely on their respective drums, and 15 it is difficult to get them properly aligned and in firm engagement with the drums so as to render possible the replacing of the cover. The bands do not extend around the whole circumference of the drums and terminate in radially extending forks adapted 20 to engage the shafts in the transmission cover. The latter shafts are surrounded by coil springs which fit between the forks referred to and serve the purpose of pressing the forks apart, thereby releasing the 25 grip of the bands on their respective drums when the foot pedals are released. When the cover is to be replaced these springs must be compressed to allow them to be inserted between the forks of the bands. 30 It is the object of the present invention to provide convenient tools for the proper alinement of the forks as well as for the compression of the springs which may be secured in their respective places 35 before the cover is replaced, and may be removed after the operation is completed.

With these objects in view I have illustrated the preferred form of my invention in the accompanying drawing, in which 40 Figure 1 represents a side elevation of the compressing tool in its position with reference to the bands; Figure 2 an end elevation of the same; Figure 3 a top plan view of the transmission drums and bands, the 45 latter being shown as properly alined by means of my clamping tool; Figure 4 a

detail view of my clamping tool, and Figure 5 another detail view of the same tool looking at it from the end. While I have shown only the preferred form of my invention, I wish to have it understood that various changes or modifications may be made within the scope of the claims hereto attached without departing from the spirit 60 of the invention.

My compressing tool (1) comprises a pair of tongs (2) and (3) joined at one end by means of the pin (4), a spring (6) tending to push the tongs apart while a lever (7) is used to force the tongs together. 65 The latter is pivotally mounted as shown at (8) between two guide members (9) rigidly secured to one of the tongs by means of a pin (11), and is provided with a cam (12) engaging the outside of the other tong 70 so that it forces the two tongs together if its handle (13) is moved from a horizontal position into the vertical position shown in Figure 1.

The lower ends of the tongs terminate in 75 parallel flat plates (14) provided at their lower extremities with registering recesses (16) adapted to engage the shafts (17) actuated by the foot pedals, not shown in the drawing, at opposite ends of the springs (18) so that the latter springs may be compressed when the lever handle (13) is moved upward.

A particularly novel feature of my compressing tool are the centering rods (19) 80 which serve the purpose of maintaining the compressed springs in a position mid-ways between the abutments (21) of the transmission cover and the confining nuts (22). The latter rods penetrate the plates (14) 85

in transverse direction and are adapted to slide in the perforations (23). They are provided with suitable heads (24) at both ends so as to limit the opening of the tongs beyond a desired degree. At least three 90 of these rods should be provided to insure perfect operation. It will be remembered

that these rods are slidably mounted in the plate but this sliding motion is limited by means of collars (26) provided on the rods 95 between the tongs in such a manner that the central rod is allowed to slide freely through one of the tongs only, while the two outside rods are allowed to slide through the other tong only so that when the tongs 100 are compressed the head of the central rod will be forced to one side engaging the cen- 105

tral abutment (21) previously mentioned, while the heads of the two other rods are forced into the opposite direction engaging the nuts (22). If all the rods are of the same length the compressed springs will be forced into a central position relative to the abutments (21) and the nuts (22).

Looking at the tool as presented in Figure 1, it will be seen that when the tongs are put in their proper place the lifting of the lever handle (13) will develop a tendency for the right hand tong to be lifted out of its place, and to prevent this I provide a hook (27) adapted to engage the central shaft (17) as soon as the operator begins to press on the lever. This result is brought about in the following manner:

The perforations (23) engaging the heads (24) of the rods (19) are countersunk and the heads tapered so as to register with the countersunk perforations and to slightly project beyond the surface of the plates (14). The hook (27) is pivotally mounted on the outside of the plate (14) by means of a pin (28), and has an extension (29) carrying a tapered lug (31) held in engagement with one of the heads (24) by means of a spring (32). Normally the hook (27) is disposed in such a manner that it will clear the central shaft (17) when the tool is put in its place. But as soon as the operator begins to force the lever handle (13) upward the heads (24) of the rods (19) lose their firm contact with the countersunk holes (23), and the tapered lug (31) at the end of the extension (29) is then forced downwardly between the head (24) of the rod and the plate (14), which motion causes the hook (27) to catch the central shaft (17) from below and to prevent the tilting of the tool.

The second tool necessary to complete the operation is the clamp (36) illustrated in Figures 3 to 5. It is very simple in its construction and comprises merely two L-shaped metal members (37) and (38), the two horizontal beams (39) of which lie flat against each other while the vertical beams (41) extend in spaced and parallel relation. The horizontal members (39) are held together by means of a coil spring (43) which allows of longitudinal motion of the horizontal arms relative to each other, but prevents angular motion. Suitable transverse projections (44) prevent the horizontal members from being withdrawn and also furnishes convenient holds for the fingers of the operator, enabling him to compress the spring (43). The advantage of this construction will appear immediately. The operator may set the two arms (41) as far apart as is necessary to allow them to engage the forks (46) extending radially from the bands (47). After all these forks which are intended to receive the shafts (17) in

the transmission cover previously referred to are confined between the two vertical beams (41), the operator may force them together by applying pressure on the horizontal members along a longitudinal line, in which operation he will be assisted by the spring (43). The forks (46) of the bands tending to force the two beams (41) apart will apply their pressure in the wrong place and will develop a tendency only for the horizontal beams (39) to move angularly relative to each other, which motion can be successfully stopped by a comparatively light spring (43).

The whole operation should be easily understood from the foregoing description. To replace the transmission cover the operator first revolves the transmission bands so that the prongs (46) are approximately aligned with each other, sets his clamp so as to comfortably span all the forks and applies the same. After forcing the vertical beams together the bands will be firmly held in a proper position to receive the shafts (17) of the transmission cover. The operator now applies his tongs to the shafts (17), compressing the springs so that the latter occupy a position midways between the abutments (21) and the nuts (22) when the cover may be moved into its place without any difficulty. The removal of the tools completes the operation.

I claim:

1. Means for compressing a plurality of springs mounted on parallel shafts comprising a pair of tongs pivotally connected at one end and terminating in flat and parallel jaws, having spaced recesses therein adapted to engage the springs at opposite ends, two guiding members for one of said tongs straddling rigidly secured to the other and having a lever pivoted therebetween for forcing the tongs together whereby the springs are compressed, and spring means for opening the tongs.

2. Means for compressing a plurality of springs mounted on parallel shafts between stationary elements, comprising a pair of pivotally connected tongs terminating at one end in flat and parallel jaws, having spaced recesses therein adapted to engage the springs at opposite ends, means for forcing the tongs together whereby the springs are compressed and means associated with the jaws for centering the same relative to the stationary elements.

3. Means for compressing a plurality of springs mounted on parallel shafts between stationary elements, comprising a pair of pivotally connected tongs terminating at one end in flat and parallel jaws having spaced recesses therein adapted to engage the springs at opposite ends, means for forcing the tongs together whereby the springs are compressed and means associated with the

5 jaws for centering the same relative to the stationary elements comprising transverse pins secured in either jaw and slidably extending through the other jaw so as to engage the opposing stationary element.

10 4. Means for compressing a plurality of springs mounted on parallel shafts between stationary elements, comprising a pair of pivotally connected tongs terminating at one end in flat and parallel jaws adapted to engage the springs at opposite ends, means for forcing the tongs together whereby the springs are compressed, transverse pins secured in either jaw and slidably extending 15 through the other jaw so as to engage the opposing stationary element and to thereby center the jaw, and spring-actuated lever means for securing one of the jaws to a shaft and permitted to operate when the jaws are 20 compressed.

25 5. An adjustable clamp, comprising two L-shaped members having their vertical beams disposed in spaced relation and their horizontal beams alongside each other, and a coiled spring wound on the latter two beams allowing of their longitudinal motion relative to each other only when actuated along said longitudinal line.

30 6. An adjustable clamp, comprising two L-shaped members having their vertical beams disposed in spaced relation and their horizontal beams alongside each other, and a coiled spring wound on the latter two

35 beams allowing of their longitudinal motion relative to each other only when actuated along said longitudinal line, transverse studs at the end of either horizontal beam facilitating the manual operation of the device.

40 7. Means for compressing a plurality of springs mounted on parallel shafts between stationary elements, comprising a pair of tongs adapted to engage the springs at opposite ends, means for forcing the tongs together whereby the springs are compressed and means associated with the tongs for 45 centering the same relative to the stationary elements, comprising transverse pins secured in either tong and slidably extending through the other tong so as to engage the opposing stationary element. 50

55 8. Means for compressing a plurality of springs mounted on parallel shafts between stationary elements, comprising a pair of tongs adapted to engage the springs at opposite ends, means for forcing the tongs together whereby the springs are compressed, transverse pins secured in either tong and slidably extending through the other tong so as to engage the opposing stationary element and to thereby center the 60 tongs and spring actuated lever means for securing one of the tongs to the shaft and permitted to operate when the tongs are compressed.

MILES McINTYRE.
